CLAIM

The ornamental design for a reader with feeder for
electronic filing system, as shown and described.

DESCRIPTION

FIG. 1 is a top plan view of the reader with feeder for
electronic filing system showing my new design;
FIG. 2 is a bottom plan view thereof;
FIG. 3 is a front elevational view thereof;
FIG. 4 is a rear elevational view thereof;
FIG. 5 is a right side elevational view thereof;
FIG. 6 is a left side elevational view thereof;
FIG. 7 is a top, front, right side perspective view
thereof.
